UNITED STATES PATENT OFFICE.

JOHN McMULLEN, OF BUFFALO, NEW YORK, ASSIGNEE OF ONE-HALF TO JOHN H. THOMAS, OF NEW YORK, N. Y.

SAFETY BRAKE-BEAM SUPPORT FOR RAILWAY TRUCKS.

Application filed September 18, 1925. Serial No. 57,095.

My invention refers to a novel emergency supporting means for railway car brakes, and consists in providing simple and effective mechanism for preventing the dropping 5 of the brake beams to the track or roadbed in case of accidental breakage of any of the suspension means thereof.

A device which suspends a bar beneath two 10 brake beams has been found very advantageous; but it is necessary to provide against the displacement of the bar by wear and the constant vibration of a moving truck, and to that end I have devised a novel 15 and very efficient fastening device for the bar which cannot be lost or destroyed by wear or continued use.

My invention therefore consists essentially 20 in the construction, arrangement and combination of various parts, and in numerous 25 details and peculiarities of the same, substantially as will be hereinafter fully described and claimed.

In the accompanying drawing illustrating 30 my invention:

Figure 1 is a plan view of a portion of a 35 car truck, including the spring plank, the brake beams and some adjacent parts, and the emergency supporting angle beams, much of the same being in outline merely.

Figure 2 is a sectional side elevation of 40 the same on the line 2, 2, of Figure 1 and represents more fully the details of the fastening device forming my present invention.

Figure 3 is a sectional side elevation on 45 the line 3, 3, of Figure 1.

Figure 4 is an enlarged cross section, in 50 partial side view on the line 4, 4, of Figure 1.

Figure 5 is a detail plan view on the line 55 5, 5, of Figure 3.

Figure 6 is a detailed side view of one 60 of the apertured hangers.

Figure 7 is a perspective view of one of 65 the slotted locking members.

Similar characters of reference designate 70 corresponding parts throughout all the different figures of the drawings.

In the drawings the brake beams are 75 shown at 4, 4; tension rods at 5, 5; and supported parts of the frame at 6; these being merely a few parts in conventional outlines to indicate the general mechanism of a car truck and brake beams, without giving the details of the side frames, but sufficient to 80 show the application and function of my in-

vention, and enable it to be understood and practised.

Connecting the frames that are essential to constitute a truck is a spring or sand plank 1 in the form of a channel, having 85 raised parallel flanges 2, 2, at the edges. Near each end of the sand plank 1 are depending hangers 3, the upper ends 7 of which are hooked over the flanges 2 of the channel plank 1 said hangers 3 being secured to the flanges 2 by means of bolts 1^a. Each hanger 3 drops a certain distance below the sand plank 1 and this lower portion is provided with an angular or preferably 90 right angled aperture, having a vertical part 10 and a horizontal part 11, the part 10 being usually wider than the part 11.

Supported in the right angled apertures of the hangers 3 that are opposite to each other at each side of the truck, as shown in 95 Figure 1, is a horizontal beam of angle iron, which is passed horizontally through the apertures in the hanger, and which can easily be moved longitudinally. There are thus two of these beams, and each one has a horizontal part 8 that passes through the horizontal part 11 of the aperture in the hangers and a vertical part 8^a that passes through the vertical part 10 of the aperture in each 100 hanger.

It is of the highest importance moreover 105 that these angle beams when once they have been properly positioned, should be immovably kept in such position until for any reason it becomes necessary to take them out or adjust them, and for the purpose of keeping them firmly in such position I have devised special means for doing this effectively. To this end the horizontal member 8 of each bar is provided with a pair of lateral notches 9, 110 one corresponding to each hanger with which the bar is used, so that when the bar 8 has been passed longitudinally through the horizontal slots 11 of the apertures in the hangers, this endwise movement will be adjusted 115 so as to bring the notches 9 directly opposite to the vertical lines of the depending portions of the hangers, as clearly shown in Figure 2, and then the bar will be caused to move horizontally, laterally, so that the member 8 slides laterally in the horizontal slot 11 of the hanger apertures, thus making the notches 9 receive and embrace the sides of the hangers to a certain extent, a movement 120 which will cause the vertical member 8^a of 110

the bar to be pressed against one side of the wider vertical slots 10 of the hanger apertures. This leaves a space between the member 8^a and the opposite sides of slots 10, the 5 slots 10 being wide enough for the purpose, and substantially wider than slots 11. Into the spaces thus left in slots 10 I insert a locking block like that shown in Figure 7, which is a proper thickness for the purpose, and 10 which is simply a square block, cut with short opposite slits to leave ears or parts 13, 13, which when the block is in place in a slot 10, as shown in Figures 4 and 5, may be bent at right angles to the face of block 12, and brought around against opposite 15 faces of the hanger 3, so that as indicated in Figure 5 the parts 13, 13, form embracing lips with the hanger and lock the block 12 in the slot 10 so that it cannot be shaken out. 20 The angle bar is in this way closely and effectively locked to the hangers and cannot be removed therefrom until the inturned ears 13 are straightened out again and the block 12 is taken out of the slot 10. In this 25 way I utilized the great advantage of the safety bar below the brake beams in a railway truck by making it impossible for the safety bar to become dislodged from its normal attitude by wear or undue oscillation. 30 The bars and hangers are similarly applicable on each side of the truck as will be

evident from the foregoing description, and the selected specimens or forms may be quickly modified without departing from my invention, the breadth of which is substantial 35 and allows many changes.

Having thus described my invention what I claim as new and desire to secure by Letters Patent, is:

1. In an emergency brake beam support, 40 the combination of a hanger having an aperture formed with a horizontal and vertical slot, and a bar supported by said hanger, said bar having a horizontal notched member and a vertical member and adapted to be 45 inserted in the apertured hanger, and a locking block also insertable into the apertured hanger alongside of the bar.

2. In a safety brake beam support, the combination with a truck frame and brake 50 beam, of a channeled sand plank, rectangularly apertured hangers carried by the sand plank, notched bars of rectangular form which are passed through the apertures in the hangers, and locking blocks for insertion 55 in the apertured hangers to lock the bars therein, said blocks having integral bendable lips to embrace the walls of the hangers.

In testimony whereof I hereunto affix my signature.

JOHN McMULLEN.
